APPARATUS FOR CUTTING MATERIAL

Vincent A. Rayburn, Baltimore, Md., assignor to
Western Electric Company, Incorporated, New
York, N. Y., a corporation of New York

Application February 12, 1946, Serial No. 647,150

13 Claims. (Cl. 164—61)

1

This invention relates to apparatus for cutting material, and more particularly to apparatus for cutting a strip from a sheet of material.

In processing of rubber or rubber-like compounds, such compounds are sometimes mixed and rolled in a rubber mill which rolls the compound into the form of a sheet. The sheet is sometimes cut into a continuous strip which is drawn from the mill. In the past, it has been difficult to gage the thickness of the strip as it is taken off the mill in order to keep the strip from being too thick. Also, strips of compounds of types which adhere tightly to the mill have been difficult to peel off of the mill, while strips of compounds of types which adhere very little to the mill tend to sag as they are formed and thereby tend to fold as they are advanced from the mill.

An object of the invention is to provide new and improved apparatus for cutting articles.

Another object of the invention is to provide apparatus for cutting a strip from a sheet of compound, to gage the thickness of the material being cut, to support the compound so as to prevent sag as it is cut into a strip and to peel the strip from a mill roll on which it was formed.

An apparatus forming a specific embodiment of the invention includes a pair of spaced cutting discs mounted rigidly on a shaft. A peeler roll is rotatably mounted on the shaft between the cutting discs. The ends of the shaft are mounted in a pair of self-aligning bearings, which are urged individually toward a mill roll which supports a sheet of material. The cutting discs serve to cut a strip from the sheet of material and the peeler roll limits the depth of cut of the cutting discs and thereby limits the thickness of the strip. The peeler roll also supports the strip at a point adjacent to the mill roll so as to prevent sag, and permits the strip to be peeled from the mill roll by a pull on the strip substantially perpendicular to the mill roll. Advancing rolls pull the strip over the peeler roll substantially perpendicular with respect to the mill roll and the sharp curve the strip makes as it leaves the mill roll aids in severing the strip from the sheet. The self-aligning bearings are supported by a frame which may be swung into operative position with respect to the mill or may be swung to one side to provide access to the mill.

A complete understanding of the invention may be obtained from the following detailed description of an apparatus forming a specific embodiment thereof, when read in conjunction with the appended drawings, in which:

2

Fig. 1 is a fragmentary front elevation of an apparatus forming one embodiment of the invention;

Fig. 2 is a vertical section taken along line 2—2 of Fig. 1;

Fig. 3 is an enlarged, fragmentary, vertical section taken along line 3—3 of Fig. 2;

Fig. 4 is a horizontal section taken along line 4—4 of Fig. 1, and

Fig. 5 is an enlarged, vertical section taken along line 5—5 of Fig. 1.

Referring now in detail to the drawings, a strip 10 (Fig. 2) is cut from a sheet 11 of material by a stripper 12, and is advanced from the stripper 15 by a pair of advancing rolls 15—15. The sheet 11 is formed from a mass of compound on a roll mill having mill rolls, of which a mill roll 16 is shown. The mill roll 16 is rotated continuously in a counterclockwise direction, as viewed in Fig. 2, and the sheet 11 is formed thereon. A frame 17 of the stripper 12 is mounted pivotally on a bracket 20 secured to an end frame 18 of the mill, and may be secured by an overcenter latch 21 in an operative position indicated by the letter A (Fig. 4), in which position the frame is parallel with the mill roll 16. The stripper also may be moved to an inoperative position indicated by the letter B to provide access to the mill.

A pair of bearings 22—22 formed on brackets 23—23 secured to the frame 17 serve to support a pintle 25. Levers 26—26 are mounted on the pintle for individual pivotal movement thereon, and are urged in counterclockwise directions, as viewed in Fig. 2, by compression springs, of which 35 a compression spring 27 is shown. The compression springs 27—27 are mounted between guide abutments, of which a guide abutment 38 is shown, secured to the supporting frame, and adjustable retainers, of which an adjustable retainer 31 is shown. The adjustable retainers are mounted on rods, of which a rod 32 is shown, which are pivotally secured to the lower ends of the levers 26—26.

The upper ends of the levers 26—26 carry self-aligning bearings 35—35 (Fig. 3), which support square ends 38—38 of a shaft 36. The shaft 36 is provided with tapped shoulders 37—37 on which are threaded nuts 40—40, which secure identical cutting discs 41—41 against shoulders 50 42—42 formed on the shaft 36. The cutting discs 41—41 are provided with blunt cutting edges 43—43 formed thereon, and are secured rigidly to the shaft 36. Bearings 44—44 mounted on the shaft 36 mount a peeler roll 45 rotatably on the shaft. The diameter of the peeler roll is smaller

by a predetermined distance than the diameter of the identical cutting discs so that the peeler roll limits the depth of cut of the cutting discs.

In the operation of the apparatus described hereinabove, the sheet 11 is formed by the mill rolls 15-15 while the stripper 12 is in position B, in which position it does not interfere with an operator of the mill while milling the material. After the compound of which the sheet 11 is formed has been thoroughly worked by the mill, the stripper is swung to position A, and is latched in that position by the overcenter latch 21. In this position the levers 26-26 are urged by the compression springs 27-27 in counterclockwise directions, as viewed in Fig. 2, and the cutting discs 41-41 and the peeler roll 45 are pressed toward the mill roll 16. The blunt cutting discs cut into the sheet to such a depth as to leave two uncut thin films at points a predetermined distance apart. The operator severs the material transversely of the portion cut by the discs to form an end of the strip, and feeds the end of the strip to the advancing rolls 15-15. The advancing rolls pull the strip substantially perpendicularly from the mill roll 16, which action is aided by the supporting action of the peeler roll 45. As the strip is advanced over the peeler roll, the strip is bent sharply out of the plane of the sheet 11 so that the thin films, which are unsevered by the cutting discs, are ruptured.

The cutting discs 41-41 are a predetermined amount larger in diameter than is the peeler roll 45. Thus, portions of the sheet 11 which are not greater in thickness than the difference in their diameters are cut by the cutting discs to form the strip 10. The cutting discs rotate at a peripheral speed about the same as that of the mill roll 16 as they cut the strip drawn from the stripper over the peeler roll 45, which has a different peripheral speed than that of the cutting discs 41-41 and a higher rate of rotation than that of the cutting discs 41-41.

The levers 26-26 urge the ends of the shaft 36, and hence the discs 41-41 individually toward the mill roll 16. If the end of the shaft 36 on which one of the cutting discs 41-41 is mounted is urged further toward the mill roll 16 than the other end of the shaft, the shaft will not remain perpendicular to the levers 26-26 on which it is mounted. However, the self-aligning bearings 35-35 provide universal movement to the shaft and thereby prevent any binding in the bearings 35-35.

If the thickness of the portion of the sheet 11 which is being cut by the cutting discs 41-41 is greater than the difference in radii between the cutting discs and the peeler roll 45, the peeler roll will be forced by this portion of the sheet away from the mill roll 16 so that the cutting discs 41-41 will be held away from the mill roll and the sheet will not be severed. This will indicate to an operator that the mill requires adjustment, which adjustment may be then made.

The peeler roll 45 has a small radius compared with that of the mill roll 16, the peeler roll is positioned close to the mill roll, and the advancing rolls 15-15 pull the strip substantially radially of the mill roll so that the portion of the strip being pulled out of contact with the mill roll is effectively peeled therefrom. This is especially important where the compound is closely adherent to the mill roll. The sharp bending of the strip ruptures the thin films of material left after the cutting operation of the cutting discs so as to separate the strip from the remainder of

the sheet. Since the bending of the strip aids the cutting discs in severing the sheet of material, the discs may be blunt and need not be pressed with great force toward the mill roll 16. Hence, maintenance of the cutting discs and scoring of the mill roll 16 are obviated.

The peeler roll also supports the strip 10 at the point it is peeled off of the mill roll so that sagging of the material between the two cutting discs 41-41 is prevented. This function is of particular importance where the compound has a high specific gravity and is loosely adherent to the mill roll, with which type of compounds there would be deformation of the strip and possible folding thereof in passing through the advancing rolls 15-15 if the strip were not supported at the point it is drawn from the mill roll. During the severing operation, the pull of the advancing rolls 15-15 on the strip is substantially radial with respect to the mill roll 16, and the supporting and guiding action of the small radius peeler 45 aids the cutting discs 41-41 in severing the sheet 11 to form the strip 10.

The stripper 12 serves to effectively cut the sheet 11 into the strip 10 and is simple and effective in its operation and construction. The peeler roll 45 serves to support the strip 10 as it is formed and also serves to effectively gage the thickness of the strip. The different rates of speed of rotation between the discs 41-41 and the peeler roll 45 eliminate slipping of the strip 10 with respect to the cutting discs 41-41 and the peeler roll 45. The stripper 12 may be easily latched in its operative position to provide complete access to the mill. The blunt edges 43-43 of the cutting discs effectively sever the sheet by a pinching action and eliminate the danger of accidents, which danger accompanies the use of sharp knives for cutting sheets into strips.

What is claimed is:

1. In an apparatus for cutting material including an abutment for supporting a sheet of material and means for advancing a strip of material cut from a sheet of material supported by the abutment, a cutting device comprising a pair of spaced cutting elements, means for pressing the cutting elements individually toward the abutment, and a roll positioned between the cutting elements and movable with the cutting elements toward the abutment.

2. In an apparatus for cutting material including an abutment for supporting a sheet of material and means for advancing from the abutment a strip cut from a sheet of material supported by the abutment, a device for cutting a strip of a predetermined width from the sheet of material comprising a pair of cutting discs having a predetermined diameter and being spaced a predetermined distance apart, means for pressing the cutting discs individually toward the abutment, and means carried with the cutting discs for engaging the sheet of material to limit the depth of cut of the cutting discs.

3. In an apparatus for cutting material including an abutment for supporting a sheet of material and means for advancing from the abutment a strip cut from a sheet of material supported by the abutment, a device for cutting a strip of a predetermined width from the sheet of material comprising a pair of cutting elements spaced a predetermined distance apart, a roll positioned between the cutting elements, said cutting elements projecting a predetermined distance beyond the roll, and means for resiliently pressing the cutting elements and the roll toward

the abutment, whereby portions of the sheet which are thicker than said predetermined distance force the roll and thereby the cutting elements away from the abutment.

4. In an apparatus for cutting material including an abutment for supporting a sheet of material and means for advancing from the abutment a strip cut from a sheet of material supported by the abutment, a device for cutting a strip of a predetermined width from the sheet of material comprising a shaft, a pair of cutting discs of a predetermined diameter mounted on the shaft, a cylinder mounted on the shaft between the cutting discs, said cylinder having a diameter a predetermined amount smaller than that of the cutting discs, a pair of self-aligning bearings for supporting the shaft, and means for urging the bearings individually toward the abutment.

5. In an apparatus for cutting material including a movable abutment for supporting a sheet of material and means for advancing from the abutment a strip cut from a sheet of material supported by the abutment, a device for cutting a strip from the sheet of material comprising a pair of rotatable cutting discs, a roll positioned between the cutting discs, and means for mounting the roll for rotation relative to the cutting discs.

6. In an apparatus for cutting material including a movable abutment for supporting a sheet of material and means for advancing from the abutment a strip cut from a sheet of material supported by the abutment, a device for cutting a strip from the sheet of material comprising a shaft, a pair of cutting discs, a peeler roll, and means for mounting the peeler roll and the cutting discs for relative rotation on the shaft.

7. In an apparatus for cutting material including a movable abutment for supporting a sheet of material and means for advancing from the abutment a strip cut from a sheet of material supported by the abutment, a device for cutting a strip from the sheet of material comprising a shaft, a pair of cutting discs secured rigidly to the shaft, and a peeler roll mounted rotatably on the shaft in a position between the cutting discs.

8. In an apparatus for cutting material including a movable abutment for supporting a sheet of material and means for advancing a strip of material cut from a sheet of material supported by the abutment, a cutting device comprising a supporting frame, means for mounting the supporting frame pivotally so that it may be swung toward and away from the abutment, a plurality of spaced cutting elements supported by the supporting frame for cutting the sheet of material at spaced points on the abutment, and means for forcing the cutting elements individually toward the abutment.

9. In an apparatus for cutting material including a movable abutment for supporting a sheet of material and means for advancing a strip of material cut from a sheet of material supported by the abutment, a cutting device comprising a supporting frame, means for mounting the supporting frame pivotally so that it may be swung toward and away from the abutment, a pair of spaced cutting elements supported by the supporting frame for cutting the sheet of material at spaced points on the abutment, a peeler roll positioned between the cutting elements, and means for pressing the cutting elements individually toward the abutment and for moving the peeler roll with the cutting elements.

10. In an apparatus for cutting material including a movable abutment for supporting a sheet of material and means for advancing from the abutment a strip cut from a sheet of material supported by the abutment, a device for cutting a strip from the sheet of material comprising a shaft, a peeler roll mounted rotatably on the shaft, a pair of cutting discs mounted rigidly on the shaft, a pair of self-aligning bearings for supporting the shaft, a frame mounted for movement between a position adjacent to the abutment and a position away from the abutment, means for mounting the bearings on the frame and for permitting individual movement of each of the bearings with respect to the frame, and means for urging the bearings individually toward the abutment.

11. In an apparatus for cutting material including a movable abutment for supporting a sheet of material and means for advancing from the abutment a strip cut from a sheet of material supported by the abutment, a device for cutting a strip of a predetermined width from the sheet of material comprising a shaft, a peeler roll having a diameter of a predetermined size and mounted rotatably on the shaft, a pair of cutting discs mounted rigidly on the shaft a predetermined distance apart, said cutting discs having a diameter of a predeterminedly greater size than that of the peeler roll, a pair of self-aligning bearings for supporting the ends of the shaft, a frame mounted for pivotal movement between a position adjacent to the abutment and a position away from the abutment, means for locking the frame in its position adjacent to the abutment, means for mounting the bearings on the frame and for permitting individual movement of the bearings with respect to the frame, and means for urging the bearings individually toward the abutment.

12. In an apparatus for cutting material including a movable abutment for supporting a sheet of material and means for advancing from the abutment a strip cut from a sheet of material supported by the abutment, a device for cutting a strip of a predetermined width from the sheet of material comprising a shaft, a peeler roll having a diameter of a predetermined size and mounted rotatably on the shaft, a pair of cutting discs mounted rigidly on the shaft a predetermined distance apart, said cutting discs having a diameter of a predeterminedly greater size than that of the peeler roll, a pair of self-aligning bearings for supporting the ends of the shaft, a supporting frame mounted for pivotal movement between a position adjacent to the abutment and a position away from the abutment, means for locking the frame in its position adjacent to the abutment, a pair of levers carried by the supporting frame for carrying the self-aligning bearings on the ends thereof, and means for urging the bearings individually toward the abutment.

13. A cutting device, which comprises a mill roll for forming a sheet of material thereon, a pair of spaced cutting discs having a diameter of a predetermined size which is small in comparison to that of the mill roll, a peeler roll having a diameter a predetermined size smaller than that of the cutting discs, means for rotatably mounting the peeler roll between the cutting discs, means for urging the peeler roll and the cutting discs toward the mill roll so that the cutting discs slit the sheet to form a strip, and means for pulling the strip over the peeler roll

in a direction substantially radially with respect to the mill roll.
